Primary Examiner — S. Bryan Reinholdt, Jr.(74) *Attorney, Agent, or Firm* — Reed Smith LLP; Walter M. Egbert, III; Richard J. Brown(57) **CLAIM**

The ornamental design for a rangefinder display screen as shown and described.

DESCRIPTION

FIG. 1 is a front view of a first embodiment of the rangefinder display screen showing our new design.

FIG. 2 is a right front perspective view of the rangefinder display screen of FIG. 1 shown in a use configuration within an environment.

FIG. 3 is a front view of the second embodiment of the rangefinder display screen thereof; and,

FIG. 4 is a right front perspective view of the rangefinder display screen of FIG. 3 shown in a use configuration within an environment.

The dotted-dashed lines in FIGS. 1-4 depict portions of the range finder display screen that form no part of the claimed design. The broken lines in FIGS. 1-4 depict environmental subject matter that form no part of the claimed design. The oblique shade lines in the drawings depict a surface that is transparent.
